THREE PLAYER CHESS BOARD

Kenneth C. Moberg, 51 Harbor St.,
San Rafael, Calif. 94901

Filed Apr. 16, 1973, Ser. No. 351,552

Term of patent 14 years

Int. Cl. D21—01

U.S. Cl. D34—5 SS

The figure is a top plan view of a three player chess board showing my new design. The reverse side of the board is unmarked.

The board is of conventional thickness.

I claim:

The ornamental design for a three player chess board, as shown and described.
